ELECTRIC SNAP SWITCH

Filed Jan. 28, 1925

Patented Feb. 1, 1927.

1,616,000

UNITED STATES PATENT OFFICE.

ARTHUR E. RAQUÉ, OF JERSEY CITY, NEW JERSEY.

ELECTRIC SNAP SWITCH.

Application filed January 28, 1925. Serial No. 5,242.

This invention relates to an electric snap switch. The object of the invention is the production of a spring controlled snap switch whereby a rapid make and break switching mechanism is obtained. The second object of the invention is the production of a snap switch whereby a high amperage can be used. The third object of the invention is the production of a switch with 10 contact elements that are self cleaning. The fourth object of the invention is the production of a switch that can be easily and quickly clamped in place.

Fig. 1 represents an elevation of an enlarged snap switch connected to a support; Fig. 2 shows an enlarged top plan view of the switch; Fig. 3 indicates a section of Fig. 2 on the line 3, 3 with the make and break mechanism in its off or open position; Fig. 20 4 shows a section of Fig. 2 on the line 4, 4 with the make and break switch mechanism in its on or closed position; Fig. 5 indicates a top plan view of a detail as indicated in Fig. 3; Fig. 6 represents a side view of a 25 detail as shown in Fig. 3; Fig. 7 shows a top plan view of Fig. 6; Fig. 8 represents a top plan view of a detail as shown in Fig. 2; Fig. 9 shows a fragmentary portion of Fig. 4 with a modification, and Fig. 10 shows a 30 fragmentary portion of Fig. 3 on a reduced scale with a modification.

The snap switch is indicated to comprise a barrel 20 with the flattened sides 21, the upper flange 22, the axial opening 23 and the exterior threads 24. A clamping nut 28 engages the threads 24. A metallic washer 29 is interposed between the said nut and the support 30. The latter has an opening 31 through which the barrel 20 extends. A 40 second clamping nut 32 engages the threads 24 and bears on the top face of the support 30.

A binding post support is indicated with the disc shaped body portion 35 which has 45 extending therefrom the arm 36. A binding post plug 38 with its usual screw 39 is supported on the arm 36. A lead wire 40 for electric current is connected to the plug 38. A disc 43 of electric insulating material 50 rounds the barrel 20 and bears on the disc shaped body portion 35. A metallic disc 45 with the upwardly projecting adjusting wings 46 surrounds the barrel 20 and bears on the top face of the disc 43. A second 55 binding post support is indicated with the disc shaped body portion 48 which bears

on the metallic disc 45 and has formed therewith the arm 49 and the upwardly extending supporting contact posts 50. An air gap 51 is indicated between the disc 45, the portion 48 and the barrel 20. A binding post plug 52 similar to 38 is supported on the arm 49 and is provided with the usual screw 53, for the lead wire 54 of the electric circuit.

Upon the top face of the body portion 48 is supported the disc 55 of electric insulating material which has formed therein a pair of openings 56 to provide clearance for the wings 46 and the contact posts 50, and a plurality of notches 57 at its circumferential edge. A bow spring with the body portion 60 surrounds the barrel 20 and bears on the disc 55. A pair of spring arms 61 with the notches 62 at their upper ends extend from the body portion 60. An operating 70 plunger is indicated with the cylindrical upper portion 65 having the annular locking groove 66 at its top. A push button 67 is indicated at the lower end of the portion 65. The portion 65 is located in the opening 23 80 of the barrel 20.

The push button 67 can clear the threads of the nut 28. Locking plates 70 have each formed at one end of their side edges the contact jaws 71 and on one end have formed 85 the concaved locking groove 72. Locking jaws 73 extend from the other end of each plate 70. The jaws 73 engage the notches 62 of the arms 61, and the locking grooves 72 engage the locking groove 66 of the cylindrical portion 65 of the operating plunger.

A cup shaped hood 75 has formed with its lower edge the lugs 76. The lower end of the cylindrical wall of the hood 75 bears against the top face of the circumferential disc 55 and the lugs 76 are detachably locked to the notches 57 thereof. The hood 75 covers and protects the make and break switch mechanism of the snap switch.

The bow spring with the spring arms 61, 100 the locking plates 70 and the operating plunger with its push button 67 constitute the rapid make and break switch mechanism of the snap switch.

In the modification indicated in Fig. 9, 105 only a portion of the switch is shown, and is indicated with the barrel 20, the nut 32, body portion 35 of one binding post support, the disc 43 the body portion 48 of the second binding post support with its contact posts 50, the disc 55, the spring arm 61, the cylindrical portion 65 of its operating plunger 110

with its groove 66, the locking plate 70 and the hood 75. In this modification it will be noted that the disc 45 with the wings 46 are omitted.

5 To operate the snap switch, the push button 67 is pushed in as indicated in Fig. 3 to locate the contacting elements in their off or open position to break the electric circuit. When the switch is located in its on or closed 10 position the push button 67 is pulled out as indicated in Fig. 4 to close the electric circuit. When the push button is moved to its on position as indicated in Fig. 4, the locking plates 70 are pulled down, so that their 15 contact jaws 71 descend and contact with the contact posts 50 of the body portion 48 of one of the post supports, and during the movements of the plates 70 whether down or up they are maintained in proper operating 20 position by contacting with the adjusting wings 46 of the disc 45. Thereby good contact is secured between said jaws 71, and the posts 50, which are at the same time maintained clear of dust and dirt. The 25 resilience of the spring arms 61 imparts an accelerated movement to the plates 70, after they have passed their dead center on either their upward or downward movements.

It will be noted that the posts 50 are in 30 electric circuit with the binding post 52 through the body portion 48 and arm 49 of its support, and that the spring arms 61 are in electric circuit with the barrel 20 and the latter is in electric circuit with 35 the body portion 35 and its arm 36 of the binding post 38. Therefore when the contact jaws 71 contact with the posts 50, the electric circuit of the snap switch is on or closed. The air gap 51 prevents a short 40 circuit in the operating elements of the switch.

In the modification indicated in Fig. 10 only a portion of the switch is shown, and is indicated with the barrel 20 and its upper flange 22, the nut 32, the body portion 35 of

one of the binding post supports with its binding post 38, the disc 43, the body portion 48 of the second binding post support with contact posts 50, only one of which is shown, the binding post 52, the disc 55, one spring 50 arm 61 only, extending from its body portion 60, the cylindrical portion 65 of the operating plunger with its groove 66, one locking plate 70 and its hood 75.

Various modifications may be made in the 55 invention and the present exemplification is to be taken as illustrative and not limitative thereof.

Having described my invention what I desire to secure by Letters Patent and 60 claim is:

1. In a snap switch the combination of a movable plunger, contact posts in connection with one of the lead wires of the switch, spring arms in connection with the second 65 lead wire of the switch, a pair of plates with one end of each in contact relation with one of said spring arms, a plunger in contact relation with the other end of each plate, an adjusting wing adjacent to each contact post 70 for said plates and a plunger in locking relation with said plates adapted to locate them in contact with said contact posts.

2. In a snap switch the combination of a movable plunger, a pair of lead wires for 75 electric current, contact posts in connection with one of the lead wires of the switch, a spring arm in connection with the second lead wire of the switch, a plate in locking relation with said spring arm and a plunger 80 in contact relation with said plate, said plunger adapted to locate said plate in contact with said contact posts.

Signed at the borough of Manhattan, city of New York in the county of New York and 85 State of New York this 30th day of December A. D. 1924.

ARTHUR E. RAQUE.
